D12-20. OR D 13,512 EX

No. 13,512

JAN 2, 1883

UNITED STATES PATENT OFFICE.

JOHN L. POPE, OF CLEVELAND, OHIO.

DESIGN FOR A WHIFFLETREE-PLATE.

SPECIFICATION forming part of Design No. 13,512, dated January 2, 1883.

Application filed August 24, 1882. Term of patent 14 years.

To all whom it may concern:

Be it known that I, JOHN L. POPE, of Cleveland, in the county of Cuyahoga and State of Ohio, have invented and produced a new and original Design for Whiffletree-Plates, of which the following is a specification, reference being had to the accompanying engraving, forming part thereof.

My invention relates to a novel design for whiffletree-plates; and it consists in the shown contour thereof, as will be hereinafter more particularly described, and set forth in the claims.

In the accompanying engraving, A represents one half and B the other half of what are known as "pair whiffletree coupling plates." The parts A and B are both provided with ear-pieces a, which are substantially alike in contour. From the central part of each half the edges of these ear-pieces curve inwardly, as at b, then outwardly, as at c, and finally meet in a point at either extremity of the part A or B. These ear-pieces are provided with holes for attachment by screws of the plates to the whiffletree and cross-bars of vehicles.

About centrally of the part A is formed an annular ring or band, e, forming a sort of cup-

shaped part or socket, at the bottom of which, and immediately surrounding the pivot-hole, is another raised ring, i, from the top of which to the perimeter of the bottom of the cup the metal slopes gradually, as shown at o. The part B is provided at about its middle with a pivot-hole, which is surrounded by a raised ring or boss, m, and a stud-like part, n, which fits into the hole surrounded by the ring i, while the annulus m fills the socket formed by the rings i and e, when the parts are put together for use, all as well understood by those skilled in the art, and apparent from the engraving.

What I claim as new, and desire to secure by Design Letters Patent, is—

1. The part A, having a configuration substantially like that shown and described.
2. The part B, having a configuration substantially such as shown and described.

In testimony whereof I have hereunto set my hand this 5th day of August, 1882.

JOHN L. POPE.

In presence of—

J. R. CURRIER,
J. M. ODELL.
